UNITED STATES PATENT OFFICE

137,515

DESIGN FOR A CONVERTIBLE FURNITURE UNIT

Joseph Randolph, New York, N. Y.

Application January 5, 1944, Serial No. 112,194

Term of patent 14 years

(Cl. 33—1)

To all whom it may concern:

Be it known that I, Joseph Randolph, a citizen of the United States and a resident of the city of New York, in the county of New York and State of New York, have invented a new, original, and ornamental Design for a Convertible Furniture Unit, of which the following is a specification, reference being had to the accompanying drawing, forming a part thereof.

Fig. 1 is a perspective view of a convertible furniture unit, showing my design; and

Fig. 2 is a rear elevational view thereof.

Fig. 3 is a perspective view of the article, showing the upper rear portion thereof in open position.

Fig. 4 is a perspective view showing the article as it appears when extended for use as a bedstead.

I claim:

The ornamental design for a convertible furniture unit, substantially as shown and described.

JOSEPH RANDOLPH.
